UNITED STATES PATENT OFFICE.

JOSEPHINE E. TILDEN, OF MINNEAPOLIS, MINNESOTA, ASSIGNOR OF ONE-HALF TO
BERTHA L. McMILLAN, OF MINNEAPOLIS, MINNESOTA.

GAME APPARATUS.

1,141,505.

Specification of Letters Patent. Patented June 1, 1915.

Application filed April 29, 1908, Serial No. 429,980. Renewed August 12, 1914. Serial No. 856,493.

To all whom it may concern:

Be it known that I, JOSEPHINE E. TILDEN, of Minneapolis, Hennepin county, Minnesota, have invented certain new and useful 5 Improvements in Game Apparatus, of which the following is a specification.

The object of this invention is to provide a new game board with movable men or pieces which are to be used in a game entitled "Togo" or "The Game of Strategy". The game is one of skill, primarily, though 10 it is so simple that it may be easily learned by all.

The invention consists generally in a 15 gameboard substantially as described and pointed out in the claims.

In the accompanying drawings, forming part of this specification, Figure 1 is a plan view of a gameboard embodying my invention. Fig. 2 is an edge view of the same. Fig. 3 is a top view of one of the movable pieces or men. Fig. 4 is a rear view, and, Fig. 5 is a side view of the same.

The board may be of wood with inlaid 25 strips to indicate the lines or it may be of pasteboard or any other suitable material. The movable pieces or men may be made of wood of two different colors or of celluloid or any other material. Half of the men 30 must be of one color and the other half of another color, black and white, or black and red, or any color decided upon hereafter. If the men are made of wood a wood must be used which will have no visible grain, 35 since it is important that the men should all look exactly alike from the opponent's side of the board.

The board is divided into two fields. Each 40 field may be regarded as a hill with a fortress on the top and two watch towers at the base. Each field is divided into spaces by a series of parallel horizontal straight lines and a series of converging straight lines. There are five horizontal lines and seven 45 converging lines in each field. The two fields are connected by three parallel lines, and it is on these lines alone that the men may be moved across into the opponent's field. At the back and center of each field is 50 an irregular space called the "fortress" marked D. This is the space which must be occupied by an opponent's man in order to

win the game. In front of each field and to the extreme right and left is a rectangular space called the "watch tower" marked E. 55 This is a place of safety, for no man can be taken while he is occupying this space.

The drawing (Fig. 1) shows the board and a few of the men in position on the board. The men are to be placed on the intersections of the lines A and B, and in the spaces called the "fortress" and "watch towers".

The movable pieces or men are seventy in number, thirty-five for each player. These 65 men may be placed on the board in any position the player desires, according to his plan of campaign. The man is a wedge-shaped block F, with an upright rectangular piece G at the back on which the name of the man 70 is printed, (see Fig. 2). It is to be understood that the right is to be reserved to make any modification in the shape of this man if so desired. The names of the men, indicating their rank, are placed so that they can 75 be read only by the player in control and by the umpire, but not by the opponent. The umpire is the only participant in the game who can know the rank and position of both sets of men on the board. However, 80 as the game progresses, each opposing player gains clearer ideas of the rank and position of his opponent's remaining men, through the previous moves of the game.

Each side has the following men. The 85 number and rank of the men are indicated in the list below:

General	One	
Lieutenant-general	One	90
Major-generals	Two	
Brigadier-generals	Three	
Colonels	Three	
Majors	Three	
Captains	Three	95
First lieutenants	Three	
Second lieutenants	Three	
Privates	Three	
Spy	One	
Engineers	Four	
Banner	One	100
Mines	Four	

The men may be moved along the lines, A, B and C, in any direction, forward, back-

ward, or to either side, one space at a time, with the exception of the engineers, which may move either one space at a time, or any distance along an unobstructed line.

5 The mines and banner are stationary and can not be moved at any time during the game. A man may move into his opponent's field only on the lines marked C on the drawing. One man takes another (providing it

10 is of lower rank) by moving against it and occupying the space on the board left by the man removed. A man of higher rank takes one of lower rank. When two men of equal rank are moved against each other, both are removed from the board.

15

The game is played by two people acting as opponents and moving the men. An umpire decides which man is to be removed from the board when the players attack each other. The players move alternately. The umpire sits at one end of the board in a position to see readily the names of the men on both sides. The game is won when a man is moved into the "fortress" of the opponent and cannot be taken by the next move of the opponent. The game is a "tie" when either player is put in a position where he cannot move any man under the rules.

30 The rules governing the moves of each man are in general as follows:

1. The general can take every man except the spy and the mines.

2. The lieutenant-general is next in rank and can take every man except the general and mines.

3. The other men rank in the order given: major-general, brigadier-general, colonel, major, captain, first lieutenant, second lieutenant, and private, and each man can take 40 those of lower rank. None of them can take a mine.

4. The engineers are the only men which can take the mines. The engineers may move one space at a time, or they may move any distance in any direction along an unobstructed line.

45 5. The spy is the only movable man that can take the general. The spy can be taken by any man on the board except the general and the engineers.

50 6. The banner is stationary. It cannot be moved at any time during the game and has no rank of its own. It has merely the value of the man behind it in the line of attack.

55 7. The banner must be placed on the board so that it is in front of some other man. When a man moves against the banner, if it is of higher rank than the man behind the banner, in the line of attack, both the banner and the man behind it are taken from the board. For instance, if a private stands behind the banner, a colonel in front of it, a major on one side and a mine on the other, the banner has the rank of any one of these

according to the direction of attack. If the banner is left standing alone, as the game progresses, it may then be taken by any man.

8. Only movable men should be placed in the watch tower. No man can be taken while in the watch tower.

7. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

9. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

10. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

11. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

12. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

13. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

14. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

15. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

16. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

17. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

18. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

19. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

20. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

21. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

22. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

23. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

24. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

25. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

26. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

27. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

28. The mines are stationary, and cannot be moved at any time in the game. Mines cannot be set on the front line of the field. If the fortress contains a movable piece, it should not be surrounded by mines, preventing that piece from moving. The mines destroy any man moved against them except an engineer. If two or more mines are in line with each other, all are destroyed by an attack of an engineer in that direction.

interesting as the players for he alone is able to watch both sides and follow the campaign.

The following will serve to show two of the many possible arrangements of the men 5 on the field.

Private	Mine	Lieut. Gen.	Sec. Lt.	Brig. Gen.	1st Lt.	Sec. Lt.
Captain	Banner	Captain	Mine	Major	Mine	Captain
First Lt.	Engineer	First Lt.	Private	Colonel	Major	Major
Major	Mine	Engineer	General	Colonel	Maj. Gen.	Eng.
Engineer	Brig. Gen.	Private	Colonel	Sec. Lt.	Brig. Gen.	Spy

Maj. Gen.	Sec. Lt.	Major	Lt. Gen.	Colonel	Brig. Gen.	Eng.
Engineer	Mine	Colonel	Spy	Captain	Mine	Private
Sec. Lt.	Engineer	Engineer	Brig. Gen.	Brig. Gen.	Captain	Private
Banner	Mine	First Lt.	Sec. Lt.	Colonel	Major	Maj. Gen.
Private	Captain	General	Mine	Major	1st Lt.	1st Lt.

I claim as my invention:

1. A game apparatus comprising a board having a surface representing fields of battle, each field having a series of horizontal lines and a series of converging lines and parallel lines extending across the spaces between the fields, each field having an irregular space at the rear thereof designated for a fortress and in the front on the left and right of each field a rectangular space designated for watch towers, and movable pieces representing officers, privates and individuals connected with an army corps, said 10 pieces having names on their rear faces indicating the character or individual represented by each piece.
2. A game apparatus, comprising a board having a surface representing fields of battle, each field having a series of horizontal lines and a series of converging lines, and parallel lines extending across the spaces between the fields, each field having a space on the left and right designated for observers, 15 and movable pieces representing officers, privates and individuals connected with an army corps, said pieces having names on their rear faces indicating the character or individual represented by each piece.
3. A game apparatus, comprising a board having a surface representing fields of battle and movable pieces representing officers, 20
4. A game apparatus comprising a board having a surface representing a field of battle, and movable pieces representing officers, privates and implements of war, each of 25 said pieces having a name or character invisible to the opposing player during the playing of the game.
5. A game apparatus comprising a board having a surface representing a field of battle and movable pieces representing individuals or implements of war connected 30 with an army, said pieces having names or characters indicating the particular individuals or implements represented by said pieces, the names of the pieces representing the characters of both sides being invisible 35 to the opposing player.

In witness whereof, I have hereunto set my hand this 14th day of April 1908.

JOSEPHINE E. TILDEN.
